UNITED STATES PATENT OFFICE.

JOHN SCHMIDT, JR., OF PHILADELPHIA, PENNSYLVANIA, ASSIGNOR OF ONE-THIRD
TO ALBERT R. THOMPSON, OF SAN JOSE, CALIFORNIA.

COOKER.

1,397,985.

Specification of Letters Patent. Patented Nov. 22, 1921.

Application filed February 23, 1921. Serial No. 447,154.

To all whom it may concern:

Be it known that I, JOHN SCHMIDT, Jr., a citizen of the United States, residing at Philadelphia, in the county of Philadelphia and State of Pennsylvania, have invented certain new and useful Improvements in Cookers, of which the following is a specification.

My invention relates to the class of cookers especially adapted for use in the canning art.

The object of my invention is to provide a cooker having a relatively great can-capacity in proportion to its size. This I accomplish by providing a can-path which occupies substantially the whole interior area of the cooker.

My invention consists in the novel cooker which I shall now fully describe, by reference to the accompanying drawings, in which—

Figure 1 is a broken end view of my cooker, partly in elevation and partly in vertical cross section.

Fig. 2 is a broken top plan view of the same.

Fig. 3 is a detail sectional view, enlarged, of the can discharge from the switching chamber.

Fig. 4 is an end elevation showing the driving mechanism.

1 is a shell inclosing what I shall term the cooking chamber, indicated by A, and the switching chamber indicated by B. Both chambers are substantially cylindrical in cross section, and have a diameter and length dependent upon the predetermined capacity of the machine. The switching chamber is located opposite the uprising 40 quadrant of the cooking chamber, and communicates with said cooking chamber by a corridor C, also included in the shell walls, and extending substantially tangential to the top of said cooking chamber.

Within the cooking chamber, and supported by longitudinal plates 2 carried by the heads or ends of the shell are the can-rails 3, preferably of angle section. These rails are so placed and directed as to form a plurality of parallel involute can-paths each occupying a cross-sectional zone or area of the chamber throughout its length. Each path comprises an inwardly leading spiral

or involute section indicated by 4, and an outwardly leading spiral or involute section 55 4', the former inrolling and the latter unrolling, and the coils of the two portions being relatively intermediate, that is alternating, as shown in Fig. 1. The innermost coil of the inleading involute section 4 reverses 60 itself about the center of curvature and merges into the innermost coil of the outwardly leading involute section 4'. A plurality of parallel inleading can-rail paths indicated by 5 lead through the corridor chamber 65 C to the peripheral extremity of each of the inleading involutes 4 and a plurality of parallel inclined outleading can-rail paths 5' lead from each of the peripheral terminals of the outleading involutes 4', back 70 through said corridor chamber. Figs. 1 and 2. In the switching chamber B, the inclined outleading can-rails 5' respectively join by sections 6 succeeding inleading can rails 5, thus forming a plurality of angularly directed switching can-paths leading 75 successively to and from successive can-paths in the cooking chamber. Thus, if a can be fed to the first inleading path 6 in the switching chamber, it will proceed through 80 the first inleading corridor path 5 into the peripheral extremity of the first cross sectional inleading involute path 4 in the cooking chamber, and through the spiral course thereof to the central cross sectional region 85 of said chamber. Here it reverses its course and proceeds outwardly through the outleading involute path 4' of said first cross section and through the first inclined outleading corridor path 5' and through the 90 second switching chamber path 6 into the second inleading corridor path 5 and by the latter is advanced into the inleading involute section 4 of the second cross sectional path of the cooking chamber, and out 95 again through the outleading section 4' of said second path and through the second outleading inclined corridor path to the third spiral path in the cooking chamber; and so on throughout the length of the machine, until it is ready to emerge from the last path of the switching chamber. The can has thus been carried successively and repeatedly to and from the cooking chamber axis, through as many cross sectional 100 areas as may be predetermined in the orig-

inal design of the machine. The can-path thus arranged gives to the machine a maximum can-capacity relatively to its dimensions for the reason that substantially the entire interior area of the cooker is utilized.

Any suitable means may be employed to carry the cans through the cooker. I have here shown a common form of propelling means comprising an endless series of 10 pusher rods 7 separated a can-width apart and carried by side chains 8, one of which is shown in Fig. 2. The rods extend lengthwise of the chambers A and B and corridor C and move through all parallel cross-sections of the paths, being directed by suitable guides, and the center reversing sprockets 10 and terminal bight sprocket 11, to follow the designated paths.

The chains are driven from a shaft 12, 20 carrying a gear 13, Fig. 4, meshing with a gear 14 on the shaft 9, of one of the center reversing sprockets 10. In a housing 15 carried above by the switching chamber portion B of the shell 1 is a rotatable can inlet 25 valve 15', Fig. 2, mounted on a shaft 16 and adapted to receive the cans from a chute 17 and to deliver them to the first can path of said switching-chamber. Carried by the portion B below is a housing 18 in which 30 is a rotatable can-outlet valve 19, Fig. 3, adapted to receive the cans from the last can path of the switching chamber and deliver them to a discharge chute 20.

21 is a motor, Fig. 4, carried by the shell 35 1. The motor shaft 22 has a worm 23 meshing with a worm-wheel 24 on a counter shaft 24' carrying a pinion 25 which meshes with a large gear 26. The gear 26 meshes above with a gear 27 on the shaft 16 of the 40 inlet valve and below with a gear 28 on the shaft of the outlet valve 19, whereby both valves are rotated. The counter shaft 24' also carries a gear 29 which meshes with a large gear 30 on the shaft 12. The shell 45 1 may be heated in any suitable manner by a suitable medium. I have not deemed it necessary to show heating means as these are well known in this connection.

I claim:—

50 1. A cooker comprising a shell; can-rails in said shell directed to form a plurality of can paths occupying successive cross sectional areas of the shell, and each path having an involute section leading from the periphery of the shell to its axial region and there reversed in direction to form an involute section leading outwardly between the coils of the inleading section to the periphery of the shell; means for directing the 55 cans from one can path to the next successively; means for feeding the cans to the inleading section of the first can path; means for discharging them from the outleading section of the last can path; and means for 60 advancing the cans through said paths.

2. A cooker comprising a shell; can-rails in said shell directed to form a plurality of can paths occupying successive cross sectional areas of the shell, and each path having an involute section leading from the periphery of the shell to its axial region and there reversed in direction to form an involute section leading outwardly between the coils of the inleading section to the periphery of the shell; switching can-rails 70 forming can paths joining the peripheral extremity of the outleading involute section of one cross sectional can path with the peripheral extremity of the inleading involute section of the succeeding cross sectional can path; means for feeding the cans to the first of said switching can-paths; means for discharging them from the last of said switching can-paths; and means for advancing the cans through all of said paths. 75

3. A cooker comprising a shell inclosing a cylindrical cooking chamber, a cylindrical switching chamber, and a corridor chamber connecting the switching chamber tangentially with the cooking chamber; can-rails 90 in the cooking chamber directed to form a plurality of can-paths occupying successive cross sectional areas of said chamber, each path having an involute section leading from the periphery of said chamber to its axial region and there reversed in direction to form an involute section leading outwardly between the coils of the inleading section to the periphery of the chamber; a plurality of switching can-rails forming 95 paths in the switching chamber; a plurality of can-rails in the corridor chamber forming paths joining the switching paths with the peripheral extremities of the inleading and outleading involute sections of the paths 100 in the cooking chamber; means for feeding the cans to the first of the paths in the switching chamber; means for discharging the cans from the last of said can-paths in the switching chamber; and means for advancing the cans through all of said paths 105 from the inlet to the outlet. 110

4. A cooker comprising a shell inclosing a cylindrical cooking chamber, a cylindrical switching chamber, and a corridor chamber connecting the switching chamber tangentially with the cooking chamber; can-rails 115 in the cooking chamber directed to form a plurality of can-paths occupying successive cross sectional areas of said chamber, each 120 path having an involute section leading from the periphery of said chamber to its axial region and there reversed in direction to form an involute section leading outwardly between the coils of the inleading 125 section to the periphery of the chamber; a plurality of switching can-rails forming paths in the switching chamber; a plurality of can-rails in the corridor chamber forming paths joining the switching paths with 130

the peripheral extremities of the inleading and outleading involute sections of the paths in the cooking chamber; means for feeding the cans to the first of the paths

means for advancing the cans through all of said paths from the inlet to the outlet, consisting of an endless series of traveling 10 pusher bars traversing said can paths.

5 in the switching chamber; means for discharging the cans from the last of said can-paths in the switching chamber; and

In testimony whereof I have signed my name to this specification.

JOHN SCHMIDT, JR.
